P. P. KLEINDIENST

STOCKING

Filed May 2, 1925

Inventor
Percy P. Kleindienst.

By *G.W. Bradford*

Attorney

UNITED STATES PATENT OFFICE.

PERCY P. KLEINDIENST, OF BROOKLYN, NEW YORK, ASSIGNOR OF ONE-HALF TO
RAYMOND S. NORRIS, OF NEW YORK, N. Y.

STOCKING.

Application filed May 2, 1925. Serial No. 27,578.

To all whom it may concern:

Be it known that I, Percy P. Kleindienst, a citizen of the United States, residing at Brooklyn, in the county of Kings and 5 State of New York, have invented certain new and useful Improvements in Stockings, of which the following is a specification.

My said invention relates to an improvement in stockings and specifically to means 10 whereby the seam may be kept straight which appears at the back of full fashioned stockings, and which also occurs in the shape of a mock-seam on other stockings. It is found to be a matter of difficulty to keep the 15 seams straight at the back of stockings of this character and this detracts from their appearance.

Referring to the accompanying drawings which are made a part hereof and on which 20 similar reference characters indicate similar parts,

Figure 1 is a perspective of a stocking embodying my invention, and

Figure 2, a section on line 2—2 of Fig. 1. 25 In the practice of my invention a garter 10 is attached to the stocking 11, ordinarily a little below the knee, and it is found that when such a garter is correctly proportioned to the circumference of the stocking the 30 garter will prevent the stocking from being dragged to one side and thus will tend to maintain the seam in a straight line. Various methods of securing a garter to a stocking may be utilized as by sewing it on or by 35 knitting an elastic zone in the stocking. The method which at present appears to me preferable to any other consists in applying rubber latex to the stocking in a narrow zone at such a position as to be located 40 slightly below the knee of the wearer. This rubber latex may be applied in various ways as for example by spraying it on the fabric. After the latex has been applied or while it is being applied steps are taken to cure 45 it in situ so that it will form a permanent elastic band with the fabric embedded therein as clearly shown in Fig. 2. This band

will maintain its elasticity during the life of the stocking and in fact will outwear an ordinary stocking. The diameter of the garter 50 is so proportioned in the process of making that it will fit accurately and causes the stocking to make a good appearance either on the counter or as worn.

In forming the elastic zone on the stocking it will be obvious that the fabric of the stocking will be embedded in the rubber. It will be understood that this process might be carried out by means of a rubber zone 60 molded or otherwise attached to the fabric so as to embed the fabric therein and perhaps in other ways, all falling within the purview of my invention. In order that the stocking may present a good appearance the rubber of the elastic band may be colored by 65 any suitable means either to match the stocking or to harmonize with it in other ways as by a suitable contrasting color.

My invention may be changed in various respects without departing from the spirit 70 thereof and therefore I do not limit myself to what is shown in the drawings and described in the specification but only as indicated in the appended claims.

Having thus fully described my said invention, what I claim as new and desire to secure by Letters Patent, is:

1. A garment having a tubular portion with the yarns in a zone thereof embedded in an annulus of rubber, substantially as set 75 forth.

2. A garment having a tubular portion with a zone thereof embedded in an annulus consisting of an elastic vulcanized gum, substantially as set forth.

3. A stocking having a seam at the rear of the leg, and means for keeping the seam straight comprising an elastic garter having the fabric of the stocking embedded therein in a zone co-extensive with said garter, substantially as set forth.

4. A stocking having a seam at the rear of the leg, and means for keeping the seam straight comprising a garter of coherent

homogeneous elastic material having the yarns of the stocking fabric embedded therein, substantially as set forth.

5. The process of forming elastic sections in a garment having a tubular portion by spraying thereon rubber latex in an annular zone or stripe, and curing the latex, substantially as set forth.

6. The process of forming a garter for a

stocking by spraying rubber latex thereon in an annular zone, and thereafter curing the latex, substantially as set forth.

In witness whereof, I have hereunto set my hand and seal at New York, New York, this eighteenth day of December, A. D., 1924.

PERCY P. KLEINDIENST. [L.S.]
